US00D730763S

(12) **United States Design Patent**
Haapakoski

(10) **Patent No.:** US D730,763 S
(45) **Date of Patent:** ** Jun. 2, 2015

(54) **DEVICE FOR RECORDING PHYSICAL EXERCISE**

(71) Applicant: **POLAR ELECTRO OY**, Kempele (FI)
(72) Inventor: **Heli Haapakoski**, Oulu (FI)
(73) Assignee: **Polar Electro Oy**, Kempele (FI)
(**) Term: **14 Years**
(21) Appl. No.: **29/476,157**
(22) Filed: **Dec. 11, 2013**

(30) **Foreign Application Priority Data**

(57) **CLAIM**

The ornamental design for device for recording physical exercise, as shown and described.

DESCRIPTION

FIG. 1 is an isometric view of a device for recording physical exercise;

FIG. 2 is a side view of the device for recording physical exercise;

FIG. 3 is a top-end view of the device for recording physical exercise;

FIG. 4 is a front view of the device for recording physical exercise;

FIG. 5 is a rear view of the device for recording physical exercise; and,

FIG. 6 is a bottom-end view of the device for recording physical exercise.

1 Claim, 6 Drawing Sheets
